Primary Examiner — Austin Murphy*(74) Attorney, Agent, or Firm* — Boyle Fredrickson, S.C.(57) **CLAIM**

The ornamental design for a stylus, as shown and described.

DESCRIPTION

FIG. 1 is an isometric view of a stylus of indeterminate length incorporating my new design, viewed from above, in front of, and from the left side of the stylus;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The dashed broken lines shown in the figures represent portions of the stylus that form no part of the claimed design. The bracket shown in the figures represents an area of indeterminate length and forms no part of the claimed design.
